UNITED STATES PATENT OFFICE.

GARRET B. OSTERHOUT, OF PROVIDENCE, RHODE ISLAND, ASSIGNOR TO WILLCOX & GIBBS SEWING MACHINE CO., OF NEW YORK, N. Y., A CORPORATION OF NEW YORK.

TAKE-UP.

1,242,031.

Specification of Letters Patent. Patented Oct. 2, 1917.

Application filed November 12, 1914. Serial No. 871,749.

To all whom it may concern:

Be it known that I, GARRET B. OSTERHOUT, a citizen of the United States of America, and residing at Providence, in the 5 county of Providence and State of Rhode Island, have invented a certain new and useful Improvement in Take-Ups, of which the following is a specification.

My invention relates to improvements in 10 take-ups; more particularly to take-ups for sewing machines and has special reference to overseam sewing machines of the character disclosed in the patent to Merritt and Noble 967,804, August 16, 1910.

15 My invention will be readily understood from the accompanying drawing in which—

Figure 1 is a plan view of portion of a machine showing my improved take-up;

Fig. 2 is a similar view showing the take- 20 up in another position;

Fig. 3 is a vertical elevation of the same in the position shown in Fig. 1; and

Fig. 4 is a perspective of the take-up cam.

25 The two threads A and B here shown subjected to the action of the take-up may be regarded as the threads of the two loopers *h* and *k* of the patent above mentioned, although the present device is obviously 30 adaptable to other machines. The threads pass through independent guide eyes in the rod 10 to the tension devices 11—12, thence to the guide eyes in the rod 13 and past the take-up devices to the guide eyes in rod 14 35 whence they are led to the loopers or other part, as may be, in the particular machine in which the invention is embodied.

The take-up as shown, comprises a rotary element lying between the threads A 40 and B and adjustably mounted by means of a set screw 15 on the shaft 16 journaled at one end in a frame element 17. While the take-up element may be solid, it is preferable for the sake of lightness, to form it with 45 a body web 18 substantially aligned with the threads in their normal course between guides 13 and 14. This web is perforated to receive the shaft 16 and is provided on its opposite faces with peripheral cam flanges or skirts 19 and 20. For the particular machine in question it is desirable that the take-up should operate differently upon the different threads and the cams are shaped accordingly, although they may be of any 50 suitable shape to meet the particular needs

of the machine in which the take-up is installed. As here shown each cam 19 and 20 merges into the web member 18 at the points 21 substantially opposite each other on each face of the web 18.

60 The thread A coming from tension device 11 passes through one of the guide eyes in rod 13, thence over shaft 16 and on one side of the take-up to a guide eye in rod 14. Thread B passes through the other guide eye in rod 13, thence over shaft 16 on the opposite side of the take-up to the other guide eye in rod 14. When the take-up is in the position shown in Fig. 1 and the threads A and B lie against the web 18 at the points 70 21 at which the cams 19 and 20 merge into the web, the threads pass in their normal course substantially directly between rods 13 and 14. As the shaft 16 rotates however, the take-up cams spread the threads in opposite directions and the slack therein is taken up in accordance with the shape of the cams. Any tendency of the threads to ride up on the periphery of the web 18 is 75 prevented not only by the tension devices 80 which keep the thread taut, but also by the arrangement of the guide rods closely adjacent the take-up. The threads are merely displaced axially of the take-up in opposite directions along the shaft 16 by the action 85 of the cams.

The formation of the slack by the peculiar movements of the loopers or other executive parts and the co-operation of the take-up therewith is too well understood to need 90 further explanation or illustration. As above stated, the cams of the take-up may be of any suitable shape, and I do not limit my invention to the precise forms shown.

I claim as my invention:

95 1. A two thread take-up comprising a rotary member with cam surfaces arranged to enter between a pair of threads and displace the same in opposite directions, for the purpose described.

100 2. A two thread take-up comprising a rotary member having cams on its opposite faces arranged to enter between a pair of threads and displace the same in opposite directions.

105 3. A two thread take-up comprising a rotary member having means on its opposite faces adapted to enter between a pair of threads and displace the same in opposite axial directions, for the purpose described.

4. A two thread take-up comprising a rotary disk having peripheral cams on its opposite faces adapted to enter between a pair of threads and displace the same in opposite 5 axial directions, for the purpose described.
5. In mechanism of the type described, guide means for spacing apart a pair of looper threads and rotary means intermittently spacing said threads abnormally apart 10 to afford a take-up.
6. In mechanism of the type described, a guide arm having a pair of guide eyes for spacing apart a pair of looper threads and rotary means adjacent said guide arm for 15 intermittently spacing said threads abnormally apart to afford a take-up.
7. In mechanism of the type described two 20 guide arms each having a pair of guide eyes for spacing apart a pair of looper threads and rotary means arranged between the said guide arms for intermittently spacing said threads abnormally apart to afford a take-up.
8. A two-thread take-up comprising a rotary member having at each end thereof cam 25 surfaces on opposite sides of its axis of rotation, for the purpose described.
9. A two-thread take-up comprising a rotary member having at each end thereof cam surfaces on opposite sides of its axis of rotation, the cam surfaces on one end being 30 unlike those at the other end to impart a different take-up action to the thread engaged thereby.
10. A two-thread take-up comprising a 35 rotary member having at its opposite ends cam surfaces shaped to impart two independent take-up actions on a single revolution to the threads engaged thereby.
11. A two-thread take-up comprising a 40 rotary member having at its opposite ends cam surfaces shaped to impart two independent take-up actions on a single revolution to the threads engaged thereby, each cam at a given end of the rotary member 45 being of like effective shape to impart two

like take-up actions on a single revolution of said member.

12. A two-thread take-up comprising a rotary member having at its opposite ends cam surfaces shaped to impart two independent take-up actions on a single revolution to the threads engaged thereby, the take-up cams at one end being of different effective shape from those at the other end of the rotary member to impart a different 50 take-up action.

13. A two-thread take-up comprising a rotary member having at its opposite ends cam surfaces shaped to impart two independent take-up actions on a single revolution to the threads engaged thereby, the take-up cams at one end being of different effective shape from those at the other end of the rotary member to impart a different 55 take-up action, while the cams at a given end of said member are of like effective shape to impart two like take-up actions on a single revolution of said member.

14. In a mechanism of the type described affording a take-up action for a pair of 60 looper threads, a rotary take-up member engaged between said threads and having cam surfaces serving to take-up the slack in the threads during the operation of the mechanism.

15. In a mechanism of the type described affording a take-up action for a pair of 65 looper threads, a rotary take-up member engaged between said threads and having cam surfaces of dissimilar shape serving to take-up the unequal slack in said threads during the operation of the mechanism.

In testimony whereof I have signed my name to this specification, in the presence of two subscribing witnesses.

GARRET B. OSTERHOUT.
